(57) CLAIM

The ornamental design for a candle cover for beverage container, as shown and described.

DESCRIPTION

FIG. 1 is a top perspective view of our new design for a candle cover for beverage container;

FIG. 2 is a side elevation view thereof; and,

FIG. 3 is a top plan view thereof.

The portions of the candle cover for beverage container shown in broken line form no part of the claimed design. The bottom forms no part of the claimed design.

1 Claim, 2 Drawing Sheets
